CONSTANT CURRENT TRANSFORMER ACTUATED CONTROL MECHANISM

Application filed July 7, 1930. Serial No. 465,882.

This invention relates to improvements in electrical control devices especially adapted for electrically operated or actuated fluid fuel burner mechanisms and more particularly to the mechanism of a constant current transformer actuated control system such as disclosed in this applicant's prior copending application Serial No. 446,573, filed April 23, 1930, which matured into Patent 1,881,321 of October 4, 1932.

This application is a further development or refinement of certain parts of the operating mechanism as disclosed in said prior copending application. It is an object of this invention to so construct certain parts to insure the normal operation under such conditions as the necessity of the particular burner mechanism employing a burner motor requiring a heavy current demand at its starting sufficient to reduce momentarily the commercial voltage passing through the ignition switch of the control, which would otherwise deenergize the primary floating coil and cause it to drop before the motor in starting reaches its normal running speed, and where residual magnetism might momentarily hold the armature against the holding magnet after the breaking of the circuit therethrough by the opening of the stack safety switch, as well as providing positive means for insuring the opening of the ignition switch after the energizing of the holding magnet upon the closing of the circuit therethrough by the closing of the stack safety switch upon the establishment of combustion.

With these and other objects in view reference is made to the accompanying sheets of drawings which illustrate preferred embodiments of this invention with the understanding that minor detail changes may be made without departing from the scope thereof.

In the drawings:

Figure 1 is a view in front elevation of the control panel, with cover and front plate removed, similar to Figure 1 of said prior copending application, showing the improved construction of parts as contemplated by this invention, the parts being illustrated in the

positions assumed when the burner is cold or when the burner motor is idle.

Figure 2 is a view similar to Figure 1 illustrating the positions assumed by the respective parts when the burner is normally running. 55

Figure 3 is a detail view in front elevation of the improved yoke or operative connection between the primary coil of the constant current transformer and the lifting lever of the actuating mechanism, the primary coil shown in its lower position assumed when deenergized. 60

Figure 4 is a view in side elevation of Figure 3, illustrating in dot and dash lines the 65 positions of the parts assumed after the primary coil is energized and floating.

Figure 5 is a detail view in front elevation illustrating the construction of the spring and counterweight of the ignition switch carrier plate. 70

Figures 6, 7, 8 and 9 are diagrams indicating positions assumed and circuits established when the circuit is first closed to start operation, position during the ignition period, normal running position, and normal idle position, respectively. 75

With the exceptions of the particular constructions hereinafter described the parts are constructed and operate as disclosed in said prior copending application and therefore it is thought necessary only to describe in detail the improved constructions and their cooperation in general with the other parts of the control in order to show clearly the improvements over the corresponding parts in said prior Patent 1,881,321 of October 4, 1932. 80

Figures 1 and 2 show a panel 1 for mounting the control mechanism which includes a constant current transformer in which the rectangular core 2 is mounted on the rear side of the panel 1. The secondary coil 3 of the constant current transformer is stationary and rests upon the bottom portions of the rectangular core 2, as shown, while the primary coil 4 is mounted thereabove and is adapted to float thereabove when energized. 90

The respective terminals 5 of the secondary coil, only one being seen in front elevation, are adapted to be connected in the ignition 100

circuit. The respective terminals of the primary coil, not shown, are connected to the commercial line by a circuit including the customary room thermostat T of commercial design, a normally closed boiler control B of commercial design and a normally closed ignition switch 6, shown in dot and dash lines in Figure 1, so that when the room thermostat closes the circuit, to start the operation of the burner mechanism, the primary coil 4 of the constant current transformer in this control device will be energized and caused to float above the stationary secondary coil 3 at the same time setting up a constant flow of current through the ignition circuit 5^a, shown in Figures 6 to 9 inclusive.

The switch operating and actuating mechanism, as in said prior copending application, is mounted upon a base plate 7 supported on the panel 1 spaced apart a sufficient distance therefrom to allow movement of the primary coil therebehind. A yoke 8 including right angular side extensions 9 provided with pivots 10 mounted in bearings 11 struck up from the panel 1 is adapted to tilt about its pivots at the rear of the base plate 7, shown also in Figures 3 and 4. The upper portion of each side 9 is extended beyond the respective pivots to form an engaging finger 12. The yoke 8 is so mounted that its pivots 10 are approximately in line with the top of the primary coil when deenergized and resting upon the secondary coil 3. Engaging members 13 are secured diametrically opposite each other upon the upper surface of the primary coil 4 so that when the primary coil 4 is deenergized the engaging members 13 engage the engaging fingers 12 and tilt the yoke upward about its pivots, as shown in full lines in Figure 4. When the primary coil 4 is energized and floats above the secondary coil 3 the yoke 8 is free to tilt in the opposite direction about its pivots.

In said prior copending application, the floating of the primary coil freed a yoke to bodily move upward and in so doing impart a rotative movement to a lifting lever adapted to free certain other parts of the control mechanism to be caused to function. In the present construction, the floating of the primary coil 4 frees the yoke 8 to rotate in a downward direction, which movement is imparted to a lifting lever 14, corresponding to the lifting lever in said prior copending application to perform a corresponding function, in the following manner. The lifting lever 14 is pivoted at 15 upon the base plate 7 and that part which extends to the left of the pivot is enlarged to increase its weight on that side and is also provided with a bearing 16 adapted to slidably receive a connecting rod 17 secured at its lower end to a struck up portion 18 of the yoke 8, which rod is provided at its upper end above the bearing 16 with an adjusting nut 19 and

is surrounded between the under side of the bearing 16 and struck up portion 18 by a coil spring 20 of sufficient strength to normally maintain the distance between the bearing and portion 18 constant, so that when the primary coil floats and frees the yoke the weight of the yoke will, through connecting rod 17, be transmitted to the enlarged end of the lifting lever 14 and will be sufficient to rotate it about its pivot 15, and cause that portion of the lifting lever to the right of its pivot to move in an upward direction, the same as the corresponding lifting lever moved in said prior copending application upon the floating of the primary coil in that device. Likewise, when the primary coil 4 is deenergized it drops upon the stationary secondary coil 3 and in so doing the engaging members 13 thereon engage the engaging fingers 12 of the yoke 8 and rotate the front of the yoke 8 upward whereupon through the rod 17 and spring 20, the lifting lever is rotated in the opposite direction, and normally will result in a shut down or recycling of the control the same as in said prior application.

It has been found that in some types of fluid fuel burning mechanisms it is necessary to employ a type of motor making an initial heavy current demand in starting which is sufficient to reduce the commercial voltage passing through the control until the motor is running normally. In the device disclosed in said prior copending application, if this initial reduction of voltage was sufficient to deenergize the primary coil, and in certain types of motors the said reduction is sufficient to produce such a result, which must necessarily occur before the running motor circuit had been completed by the establishment of combustion, a shut down would occur.

In order to compensate for such a reduction in voltage, a dash pot 21, preferably an air dash pot such as illustrated, is provided and mounted on the panel 1 above the left hand enlarged portion of the lifting lever 14, the piston 22 of the dash pot 21 being connected by the rod 23 to a stud 24 carried on the opposite side of the lifting lever 14 preferably in line with and adjacent the bearing 16.

In the type of motor referred to the reduction in voltage is but momentary and in a short space of time the voltage becomes normal as the motor reaches its normal running. By the above described construction when a momentary reduction in voltage occurs and if the primary coil drops to tilt the yoke 8, the coil spring takes up the shock and the dash pot, being connected to the lifting lever 14, resists and slows up the rotation of the lifting lever sufficiently to allow the reenergizing and floating of the primary coil as the motor load becomes normal before the

lifting lever 14 has moved enough to render the actuating and operating mechanism inoperative.

As shown the base plate 7 mounts an ignition switch carrier plate 25, a motor switch carrier plate 26, mounting a motor switch M S, and actuating member 27 and a bell crank locking lever 28, all pivoted upon the base plate to function in the same manner as the corresponding parts in said prior copending application. Also a holding magnet E with armature 29 pivoted at 29^a having an extension 30 adapted to engage the locking lever 28 are shown mounted in the same manner as in said prior copending application. The actuating member 27 is rotated about its pivot by link 31 and bi-metallic member 32, and the ignition switch carrier plate 25 is moved to close the ignition switch thereby through the spring pressed link 27^a, as well as the locking lever 28 caused to lock the motor switch carrier plate 26 with the motor switch in closed position by the energization of the holding magnet E and through members 30 and 39 to open the ignition switch, as disclosed in said prior copending application.

The lifting lever 14 is provided on the right of its pivot with a pin 33 adapted in the upper position to be held by the locked motor switch carrier plate 26; with a stud 34 therebeyond, adapted to pass through aperture 35 in the base plate, to limit the upward and downward amount of movement of the lever; and therebeyond with a pivoted pawl 36, all similar and for similar functions as in said prior copending application.

From the foregoing it is seen that when the burner mechanism is idle, the primary coil 4 is dead and its weight upon the engaging fingers 12 has caused the yoke through spring 20 to rotate the lifting lever 14 to lift the piston 22 to the end of its stroke in the dash pot 21 and the parts are in the position of the corresponding parts as disclosed in the cold position in said prior copending application, with the ignition switch closed and the running motor switch open. The room thermostat T calls for heat by closing. The circuit through the ignition switch is closed thereby and the primary coil energized and begins to float releasing the yoke 8 to begin the depression of the left hand end of the lifting lever 14. In case of a momentary deenergization of the primary coil 4, before the motor switch is locked in closed position, its full weight falls upon the engaging fingers 12 and the impetus of the yoke to rotate the lifting lever 14 is absorbed by, first, the compression of spring 20 and then by the dash pot 21 as the spring expands so that, as the motor load becomes normal, the coil 4 will float again before the lifting lever 14 has rotated enough to cause the mechanism to shut down, whereby the control operates normally to first close the

running motor switch and then open the ignition switch. In so doing the motor switch carrier 26 as it is locked in closed position will engage the pin 33 to support the coil 4 when it becomes deenergized, as in said prior copending application. When the room thermostat opens as the desired temperature is reached, the motor switch carrier plate 26 is unlocked and the weight of the coil 4 acting upon the yoke 8 will cause the freed lifting lever 14 to assume the cold position.

Certain types of burner mechanisms require the ignition elements to be so heated that when ignition occurs the elements are within the flame of the burning fuel and, unless the ignition circuit is broken promptly after ignition of the fuel occurs, the ignition elements are subjected not only to the heat of the flame but also the heat generated by the passage through them of the ignition circuit. The continuous action of the combined heats may have a deteriorating action upon the ignition elements and to prevent the possibility of such combined heat destroying or making the elements inoperative this invention contemplates providing means whereby the ignition circuit is opened as soon as the holding magnet E is energized.

The energization of the holding magnet E is accomplished through the closing of a commercial thermally actuated stack switch, S, Figures 6 to 9 inclusive, normally open, and operated by an increase in the stack temperature as a result of combustion within the combustion chamber, all as described in said prior copending application.

The opening of the ignition circuit by the holding magnet E is accomplished in the following manner: A shoulder 37 is provided at the free end of arm 30 of the armature 29 whereby the shoulder, upon upward movement of the arm when the holding magnet is energized, will not only engage the weighted horizontal arm 38 of the locking bell crank lever 28 but also the underside of the counterweight 39 and as it is pushed up, will, through movement of the pin 42 on the counterweight 39 in the notch 43 of the switch carrier, tilt the carrier, opening the ignition switch during the normal operation, and thereafter hold it open until the holding magnet is deenergized. As in said prior copending application the counterweight plate 39 is mounted on the same pivot as the ignition switch carrier plate 25 and is engaged therewith by the pin 42 on the plate 39 received in the notch 43 of the carrier plate 25. This pin 42 is adapted to be engaged by the pawl 36 under certain conditions and function as in said prior copending application.

In order to insure a quick and positive release of the armature 29 irrespective of any residual magnetism that may exist upon the

deenergizing of the holding magnet E, and consequently insuring the prompt release of the motor switch carrier plate 26 from engagement with the locking lever 28, the 5 counterweight plate 39 is provided on the underside with a strong spring member 40. When the magnet is energized the shoulder 37 pushes upward the counterweight until it 10 engages the fixed stud 41 upon the base plate 7 and further movement of the magnet armature results in the compression of the spring member 40, so, upon deenergizing the magnet the pressure of the spring 40 imparts an 15 initial impetus to free the armature 29 to unlock the motor switch carrier plate 26.

In said prior copending application the horizontal arm of the bell crank locking lever is weighted to rotate the locking lever to unlock the motor switch carrier plate when the 20 holding magnet is deenergized and requires a manual rotation in the opposite direction to reset the device and a manual reset which upon rotation causes a swinging arm to engage the armature arm to rotate against the 25 holding magnet to lift the weighted portion of the locking lever. As a further refinement, this invention contemplates the omission of the manual reset just described and rotation of the armature by providing the 30 free end of the horizontal arm 38 of the locking lever with vertical outwardly curved portion 44 adapted to project through a slot in the side casing wall and be engaged by the hand to manually rotate the locking lever to 35 reset the device.

From the above description it is seen that this improved control mechanism while performing all the functions of that disclosed in said prior copending application and in 40 which most of the parts are of similar construction, in addition thereto, it compensates for the employment of burner mechanisms employing motors having a heavy starting load; insures a prompt and positive 45 freeing of the magnet armature upon de-energization to allow the ignition switch to close and the motor switch to open; and provides a simple and positive reset forming a part of the locking lever.

50 From the diagrams illustrated in Figures 6 to 9 inclusive, it is readily seen that, as illustrated in Figure 6, when the room thermostat T closes, a circuit is closed from the source of electricity through the normally closed boiler control B, room thermostat T, normally closed ignition switch 6 and through the primary coil 4 of the constant current transformer and back to the commercial line, as indicated in heavy lines. The 55 closing of this circuit energizes the secondary coil 3 of the constant current transformer which not only causes the primary coil to rise and float, but also energizes the ignition circuit 5^a leading from the secondary coil 3 which passes through bi-metallic member 32

and hot wire igniter I. During the ignition period while the ignition circuit 5^a is energized, the bi-metallic member 32 becomes deformed and, as shown in Figure 7, causes the motor switch M S to close, thereby setting 70 up a circuit from the commercial line from the binding post adjacent the room thermostat through the motor switch M S and through the motor back to the commercial line. When the fuel is ignited the thermally 75 actuated safety switch S responds thereto and closes, thereby closing a circuit from the binding post adjacent the room thermostat T through the holding magnet E back to the commercial line without disturbing the 80 motor circuit already established. The closing of the circuit through the holding magnet actuates its armature to open the ignition switch 6, whereby the primary coil 4 is deenergized and likewise the ignition circuit, 85 at the same time the armature of the holding magnet E locks the motor switch M S in closed position and thereby through stud 33 supports the primary coil 4. This is the 90 normal running position, as illustrated in Figure 8.

Upon the deenergizing of the ignition circuit, the bi-metallic member 32 cools and exerts tension upon the member 27 to normally open the motor switch which is held 95 closed as long as the holding magnet E is energized. Upon opening of the circuit through the room thermostat the holding magnet E is deenergized which allows the motor switch M S to be unlocked, so that 100 the same will be thrown by member 27 to open position and this movement of member 27 through link 27^a closes the ignition switch 6, as shown in Figure 9.

What I claim is:

1. A control mechanism for an oil burner having an electric motor, including a constant current transformer having a stationary and a movable coil, a switch in the motor circuit normally held in open position, a switch in the primary circuit of the transformer normally closed, whereby the closing of the circuit to the control energizes the transformer and causes one coil to float above the other, means operative as a result of 115 transformer energization to close the motor switch and thereafter open the transformer switch a predetermined time after the initial floating of the coil, means rendered operative by the weight of the floating coil upon the deenergization of the transformer prior to the expiration of said predetermined time to open said motor switch, and additional means to retard the action of the deenergized coil during said predetermined time.

2. In a device of the character disclosed, including a burner having a motor and an electrically operative igniter, a switch in the motor circuit normally open, an ignition switch normally closed, means operable upon 120

- closing the circuit through the ignition switch to close the motor switch to operate the burner mechanism and thereafter permit the breaking of the circuit through the ignition switch, means controlled by the normal operation of the burner mechanism to lock the motor switch in closed position during the continued normal operation of said mechanism including a normally open thermal switch operative to close upon ignition of the fuel, a holding magnet in the circuit of said last named switch, an armature actuated by energizing said holding magnet to lock the motor switch closed, and open the ignition switch, and said thermal switch opening to deenergize said magnet and release said armature to release said motor switch to open and said ignition switch to close when the burner flame fails, and additional means to prevent residual magnetism retarding the unlocking of the motor switch and freeing the ignition switch upon deenergization of the holding magnet including a spring acting upon the lock engaging arm of the armature.
3. In a device of the character disclosed, including a burner having a motor and an electrically operable igniter, a switch in the motor circuit normally open, an ignition switch normally closed including a snap action switch operating mechanism and counter weight, means operable upon closing the circuit through the ignition switch to close the motor switch to operate the burner mechanism and thereafter permit the breaking of the circuit through the ignition switch, means controlled by the normal operation of the burner mechanism to lock the motor switch in closed position during the continued normal operation of said mechanism including a normally open thermal switch adapted to close upon ignition of the fuel, a holding magnet in the circuit of said last named switch, an armature actuated by energizing said holding magnet to lock the motor switch closed and lift the counter weight of the snap action mechanism, to open and hold open the ignition switch, said thermal switch opening to deenergize said magnet and release said armature to release said motor switch to open and said ignition switch to close when the burner flame fails, and additional means to prevent residual magnetism retarding the unlocking of the motor and ignition switches upon deenergization of the holding magnet including a spring upon said counter weight acting upon the lock engaging arm of the armature.
4. In a device of the character disclosed, including a burner having a motor and an electrically operable igniter, a switch in the motor circuit normally open, an ignition switch normally closed including a switch operated mechanism and counter weight, means operable upon closing the circuit through the ignition switch to close the motor switch to operate the burner mechanism and thereafter permit the breaking of the circuit through the ignition switch, means controlled by the normal operation of the burner mechanism to lock the motor switch in closed position during the continued normal operation of said mechanism including a normally open thermal switch adapted to close upon ignition of the fuel, a holding magnet in the circuit of said last named switch, an armature actuated by energizing said holding magnet to lock the motor switch closed and lift the counter weight of the snap action mechanism, to open and hold open the ignition switch, said thermal switch opening to deenergize said magnet and release said armature to release said motor switch to open and said ignition switch to close when the burner flame fails, and additional means to prevent residual magnetism retarding the unlocking of the motor and ignition switches upon deenergization of the holding magnet including a spring upon said counter weight acting upon the lock engaging arm of the armature.
5. In an ignition and control means for fluid fuel burning devices having a motor and an electrically operable igniter including a motor switch, an ignition switch, and a constant current transformer, in circuit with said igniter and ignition switch, including a stationary low voltage coil with a bimetallic actuating means in circuit with said coil and with said igniter, means connected to said actuating means to operate to close the motor switch and open the ignition switch, a floating high voltage coil means operated by the weight thereof arranged to cause the motor switch to be closed by the bimetallic means when said coil is floating and to prevent the motor switch from closing when it fails to float, means including an air dashpot for delaying the sinking action of the floating coil from operating to open the motor switch during a limited period, a holding magnet and means operated thereby arranged to lock the motor switch in either on or off position as it may be at the time the holding magnet is energized and to also open the ignition switch and hold it open as long as it is energized.
6. In a device of the character disclosed, including a burner having a burner motor and an electrically operable igniter, a switch in the motor circuit normally open, an ignition switch normally closed including a switch operating mechanism and counter-weight, means operable upon closing the circuit through the ignition switch to close the motor switch to operate the burner mechanism and thereafter permit the breaking of the circuit through the ignition switch, means controlled by the normal operation of the burner mechanism to lock the motor switch in closed position during the continued normal operation of said mechanism including a normally open thermal switch adapted to close upon ignition of the fuel, a holding magnet in the circuit of said last named switch, an armature actuated by energizing said holding magnet to lock the motor switch closed and lift the counter weight of the snap action mechanism, to open and hold open the ignition switch, said thermal switch opening to deenergize said magnet and release said armature to release said motor switch to open and said ignition switch to close when the burner flame fails, and additional means to prevent residual magnetism retarding the unlocking of the motor and ignition switches upon deenergization of the holding magnet including a spring upon said counter weight acting upon the lock engaging arm of the armature.

holding magnet to lift the counterweight of the switch operated mechanism to open and hold open the ignition switch and to lock in closed position the motor switch, and 5 said thermal switch opening to deenergize said magnet and release said armature to release said ignition switch to close and said motor switch to open when the burner flame fails, and upon a momentary interruption of current to the device when the burner mechanism is normally operating, the momentary deenergization of the holding magnet releases said armature to allow the motor and ignition switch operating means to 10 return the motor switch to open position and the ignition switch to closed position and the immediate resumption of current re-energizes the holding magnet to actuate the armature to hold open the motor switch and 15 lift the ignition switch counterweight to tilt the ignition switch to open position whereupon combustion ceases and the thermal switch opens to de-energize the holding magnet to release the armature to free the motor 20 switch and release the ignition switch counterweight to allow the ignition switch to return to closed position and the control recycles in going through the movement of a 25 normal start.
